US0D1038497S

(12) **United States Design Patent** (10) Patent No.: **US D1,038,497 S**
(45) Date of Patent: ** *Aug. 6, 2024

(54) **ELECTRONIC ATOMIZING DEVICE**

(71) Applicant: **Shenzhen Smoore Technology Limited**, Shenzhen (CN)

(72) Inventors: **Baosheng Lai**, Shenzhen (CN); **Lili Zuo**, Shenzhen (CN); **Chaoyong Bie**, Shenzhen (CN); **Yu Liu**, Shenzhen (CN); **Zhanhui Sun**, Shenzhen (CN)

(73) Assignee: **SHENZHEN SMOORE TECHNOLOGY LIMITED**, Shenzhen (CN)

(*) Notice: This patent is subject to a terminal disclaimer.

(**) Term: **15 Years**

(21) Appl. No.: **29/834,099**

(22) Filed: **Apr. 9, 2022**

(57) **CLAIM**

The ornamental design for an electronic atomizing device, as shown and described.

DESCRIPTION

FIG. 1 is a perspective view of an electronic atomizing device showing my design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the electronic atomizing device that form no part of the claimed design.

1 Claim, 8 Drawing Sheets
